UNITED STATES PATENT OFFICE.

SAMUEL KOPS, OF NEW YORK, N. Y.

BONE-POCKET.

No. 849,137.

Specification of Letters Patent.

Patented April 2, 1907.

Application filed October 16, 1906. Serial No. 339,150.

To all whom it may concern:

Be it known that I, SAMUEL KOPS, a citizen of the United States, residing at the borough of Manhattan, city, county, and State of New York, have invented an Improvement in Bone-Pockets, of which the following is a specification.

Pockets for securing bones to corsets are usually made as parts of the corset by sewing strips of fabric to the under or back surface of the fabric body into which the bones are slipped, and one or both ends are then sewed down to place. Bones for corsets and waists have been incased in suitable material to prevent the same rusting and prior to placing the same in ordinary bone-pockets.

The device of my invention is adapted for sale to be attached to a corset or waist or to be attached directly to a corset in the manufacture thereof, and the construction is of such nature that a particular manner of connecting the same to the corset or waist has to be followed or carried out and which in the performance thereof imparts certain functions or characteristics to the bone-pockets and bones in relation to the article to which the same are connected.

In carrying out my invention each bone-pocket is made alike and is to be secured alike and contains two parallel bones. I employ a strip of fabric materially longer than the bones and more than twice as wide as the over-all width of the two bones when spaced apart the desired distance, so that when folded over the respective edges appreciably overlap. I employ a lining-strip of fabric within the aforesaid folded fabric of a width agreeing with the over-all width of the spaced-apart bones.

In making up the bone-pocket the two bones are laid in the first foldable strip upon the lining-strip and the edges are folded over and overlapped, and a line of sewing is made between the bones through the overlapped edges, the lining-strip and the first aforesaid strip, the same being sufficient to hold the parts together. The respective ends are then folded over entire beyond the ends of the bones and toward the surface having the folded edges. The pocket is then in condition for sale and use or to be at once attached to a corset or waist in the course of the manufacture of the same.

In attaching this bone-pocket to a corset or waist the surface having the overlapped edges and overturned ends is laid down upon

the back face of a corset or waist and is secured thereto by at least two parallel lines of sewing lengthwise of the pocket along the respective edges and outside of the bones and preferably also by a central line of sewing between the bones. These sewed lines extend from end to end of the bone-pockets through the overturned ends, and it will be observed that these overturned ends come between the bones and the corset or waist to prevent the bones wearing or pushing through outward and also that the two thicknesses back of the bones perform the same function inward, and in this construction and after attachment of the device to a corset or waist there are at least two thicknesses of fabric at each side of the bones.

In the drawings, Figure 1 represents the parts composing my invention, with the bones laid in place upon the lining-strip. Fig. 2 shows the edges as folded over with a line of sewing centrally between the bones. Fig. 3 is a view similar to Fig. 2, but with the respective ends overturned against the surface where the edges of the strip of fabric overlap. Fig. 4 is an edge view of the parts shown in Fig. 3. Fig. 5 is a cross-section at the dotted line $x-x$ of Fig. 1. Fig. 6 is a cross-section at the dotted line $y-y$ of Fig. 2. Fig. 7 is a cross-section at the dotted line $z-z$ of Fig. 3. Fig. 8 is a broken elevation of the bone-pockets upon the under surface of the corset or waist, and Fig. 9 is a cross-section at the dotted line $x'-x'$ of Fig. 8.

a represents a main foldable strip of fabric, which is materially longer than the bones and is more than twice as wide as the over-all width of the two bones when spaced apart the desired distance. This strip is to be folded over along its respective edges 2 3, so that these edges appreciably overlap over the space intervening between the bones. *b* represents a lining-strip of fabric substantially as long as the strip *a* and of a width substantially agreeing or slightly greater than the over-all width of the spaced-apart bones, the edge of this fabric indicating the line of fold upon which the sides or edges of the fabric strip *a* are to be folded, and *c d* represent the bones spaced apart and lying upon the strip *b*. These bones are considerably shorter than the strips of fabric *a b*, so that their respective ends leave an appreciable margin of fabric at the respective ends *c d*. These bones are to be spaced apart and their outer edges also spaced apart from the

outer edges of the fabric strip *b*. In assembling these parts the strip *b* is laid upon the strip *a* and the bones are laid upon the strip *b* in the manner shown in Fig. 1. The edges 5 of the strip *a* are then folded over at the respective edges of the strip *b*, and they overlap centrally upon the bones, and a line of sewing 4 is run the complete length of the strips *a b* through the overlapped edges 2 3 of 10 the fabric *a* between the bones, through the fabric *b*, and centrally through the fabric *a*, so as to bring the parts into the position shown in Fig. 2. The parts are thus held together, and the frictional grip of the fabric is 15 generally sufficient to prevent the bones shifting within the pockets. The respective ends *a' a²* of the combined strips *a b* are then folded over beyond the ends of the bones, the fold being toward the side of the overlapping 20 edges of the strip *a*, and when this is done the parts are in the position shown in Fig. 3, and the bone-pocket is then in condition for sale and application to a corset or waist, as the user desires, or to be at once attached to 25 a corset or waist in the course of manufacturing the same for sale.

In Figs. 8 and 9, *e* represents a part of the fabric of a corset body or waist, and in the manner of attaching the completed bone-pocket, as shown in Figs. 3 and 4, the surface illustrated in Fig. 3 is to be laid down upon the inner surface of the corset or waist and to be sewed thereto.

I have shown at 5 and 6 edge lines of sewing, which secure the bone-pocket to the fabric body of the corset or waist, passing through the folded edge of the fabric *a*, the edges of the fabric *b*, and the fabric *e*, and I also prefer to employ a center line of sewing 35 40 45 50 55 60 65 70 75 80 85 90 95 100 105 110 115 120 125 130 135 140 145 150 155 160 165 170 175 180 185 190 195 200 205
